PIVOT CENTRES

James Hadfield, Romiley, Chester, England, assignor to Beyer Peacock & Company Limited, Manchester, England, a British company

Application May 21, 1956, Serial No. 586,150

Claims priority, application Great Britain May 24, 1955

5 Claims. (Cl. 308—137)

This invention relates to pivot centres for articulated and bogie locomotives of all types and in particular diesel-electric, diesel-hydraulic, diesel-mechanical, gas turbine and electric locomotives.

The object of the invention is the provision of an improved pivot centre of the above character, which, amongst other advantages, can be applied, for example, to bogie pivot centres on electric or diesel locomotives without restricting the basic design of the bogies or imposing limitations on the space available for traction motors or gear boxes, or for access to such transmission units for inspection and maintenance.

The invention consists broadly of a pivot centre for articulated and bogie locomotives comprising a male member and a female member, said female member including a wearing element which is mounted so as to be movable towards the male member for taking up wear, wherein said wearing element is biased in the direction for taking up wear by means of a horizontally movable wedge which engages a surface of said wearing element and is itself biased by means of a long horizontal helical spring.

In order that the invention may be the more clearly understood two pivot centre constructions in accordance therewith will now be described, reference being made to the accompanying drawings wherein:

Figure 1 is a sectional elevation of one of said constructions the section being on line I—I of Figure 2.

Figure 2 is a sectional plan of the same, with the male pivot member removed the section being on line II—II of Figure 1.

Figure 3 is a sectional elevation of the other construction, the section being on line III—III of Figure 4.

Figure 4 is a sectional plan of the same, the section being on line IV—IV of Figure 3.

Figure 5 is a cross section of the same, the section being on line V—V of Figure 4.

Referring first to Figures 1 and 2 the construction comprises a female pivot member 1, 2 which is mounted on the frame structure 3 of the bogie or truck or alternatively the swing bolster of the bogie or truck if such is provided, and a male pivot member 4 attached to the superstructure of the locomotive which extends downwards engaging the female member. The male member 4 has a flat bottom bearing plate 5 which rests on a corresponding flat bearing plate 6 at the bottom of the female member and supports the weight of the superstructure.

The male member 4 is also fitted with a renewable ring 7 in the form of a truncated cone, as in our prior Great Britain Patent No. 647,480, and the female member 1, 2 is machined to the same contour, this arrangement being designed to permit a certain amount of tilting

2

between the male and female members in both longitudinal and transverse directions.

The female member 1, 2 comprises a fixed bearing block 1 and an adjustable bearing block or wearing element 2 machined as mentioned above to the same conical contour as the ring 7 of the male member, with a clearance 8 between blocks 1 and 2 at each side to permit horizontal longitudinal movement of block 2 towards the male member as wear takes place.

10 The adjustable bearing block 2 is permanently biased towards the fixed block 1 by means of a spring loaded wedge 9 and wear on the circumferential bearing surfaces of the male and female members is thus automatically taken up.

15 The wedge 9 moves in a horizontal direction. It has its geometrical axis at right angles to the direction of movement of the adjustable bearing block 2 and its two faces are equally inclined in opposite direction with respect to said geometrical axis. One of said faces is in contact with the bearing block 2 and the other in contact with a fixed bearing block 10. The taper of the wedge 9 is so arranged that reversal of action can take place in response to the bearing blocks 1 and 2 being forced apart by the male member when the superstructure is 20 being lowered into position on the bogies or trucks and also under conditions of tilting between the male and female members in a longitudinal direction.

25 The wedge 9 is loaded by means of a long horizontal helical spring consisting of two component parts 11 and 12 arranged in series and connected by a bolt 13 passing through a longitudinal hole 27 in said wedge.

30 More particularly, the component spring part 11 is in compression between a shoulder 28 countersunk in said hole in the wedge and a head 29 on the rear end of the bolt 13, a suitable washer 30 being provided between said spring part 11 and said head 29, and the component spring part 12 is in compression between a head 31 screwed on the forward end of said bolt and a fixed surface 32 beyond the forward end of the wedge, a washer 33 being provided between said sprung part and said surface.

35 The load thus applied to the wedge is such that under all conditions of wear of the male and female pivot members there is no clearance between said pivot members in a longitudinal direction, thus eliminating all 40 “knocking” which occurs when clearance exists in pivot centres and the consequential shock loads and damage to the structure of the locomotive which can occur under these conditions. Also the pressure exerted by the bearing blocks 1 and 2 on the male member creates a frictional resistance to rotation of the male member relative to the female member which greatly assists in preventing “hunting” or oscillation of the bogie or truck in the track.

45 The female member 1, 2, the wedge 9 and the spring 11, 12 are housed in an oil-tight container which provides 50 an oil bath for the working parts. This container comprises a casting 14 having a recess 35 which contains the female member 1, 2 and the wedge 9. A cover plate 15 covers said recess 35 and the male member projects into said recess through a hole in said cover plate, with a dust 55 seal 16 between said male member and the edge of said hole.

60 The spring part 11 is also contained in said recess, but the bolt 13 projects through a wall of said recess to the outside so that said spring part 12 is outside said casting.

65 An oil-tight cover 17 mounted on the outside of said casting encloses said spring part 12. A screwed plug 18 provides access for removal of spring part 11 and bolt 13.

Referring now to the construction illustrated in Figures 3 to 5, this is the same in principle as that of Figures 1 and 2 and like references have been employed for similar parts of the two constructions. In the case of Figures 3 to 5 however a long horizontal helical spring 19 is employed actuating the wedge 9 by means of a lever 20 and compression link 21. The spring 19 is enclosed within a plunger 22 which slides in a bored hole 34 formed in the casting 14 on the side of the pivot centre remote from the wedge, and parallel to a horizontal line at right angles to the direction of travel of the adjustable bearing block 2, i.e. parallel to that diameter of the pivot centre which contains the clearances 8. The lever 20 oscillates in a second recess 23 formed in the said casting 14, about a fixed vertical pivot pin 24 between its ends. The hole 34 breaks into the recess 23 and the spring 19 is in compression between a screwed plug 25, screwed into the outer end of said hole 34, and one end of the lever 20. The compression link 21 extends from the other end of said lever to the wedge 9 through an opening 36 in the partition between the recesses 23 and 35. The pivot pin 24 is disposed so that said lever affords a mechanical advantage. This mechanical advantage and the space available to accommodate the spring 19 permits the employment of a spring of relatively light section and optimum deflection rate. All the working parts are enclosed in an oilbath constituted by the cavities 23 and 35 and the hole 34. The screwed plug 25 provides for removal of spring 19 and plunger 22 whilst the oiltight cover 26 provides for removal of the lever 20 after the cover plate 15 and pin 24 have been removed. The cover plate 15 covers both the cavity 23 and the recess 35.

In both of the above embodiments the fact that the slideable bearing block 2 can be forced to move away from the fixed bearing block 1 is of the greatest importance. For example, if excessive tilting movement should take place as might happen in the case of a derailment the sliding block 2 withdraws as required and prevents binding between the male and female members which would otherwise occur and relieves the supporting structure from excessive strains which would be caused by such binding.

The conical form of the pivot members is also of great importance since it permits a certain amount of tilting in both longitudinal and lateral directions without binding and also tends to minimise the stress created by "snatching" when starting heavy trains. This conical form in conjunction with the fact that the slideable block 2 can be forced back due to the reversible action of the wedge 9 is also of value in facilitating erection since the weight of the superstructure as it is lowered into position automatically forces the bearing blocks 1 and 2 apart during entry of the male member. Thus the assembly does not require any slackening of the spring or any manipulation of component parts.

Both embodiments are particularly valuable for application to bogies or trucks wherein design features and space restrictions require a pivot centre entirely contained within a small space in the vertical direction.

It will be seen that, in both embodiments the loading spring is parallel to the geometrical axis of the wedge, but the arrangement is such that the extent of said spring beyond either end of said wedge is much less than the length of said spring, and thus a compact design is achieved.

I claim:

1. A pivot centre for articulated locomotives and bogie locomotives, comprising a female pivot member mounted in a fixed housing and a male pivot member, said female pivot member including a wearing element which is mounted so as to be movable towards the male pivot member for taking up wear, a horizontally movable wedge engaging a surface of said wearing element and movable in a given direction for moving said wearing

element for taking up wear, two component horizontal helical springs and a coupling member, one of said springs biasing said wedge in said given direction relative to one end of said coupling member and the other of said springs biasing the other end of said coupling member relative to said housing to further bias said wedge in said given direction.

2. A pivot centre for articulated locomotives and bogie locomotives, comprising a female pivot member mounted in a fixed housing and a male pivot member, said female pivot member including a wearing element which is mounted so as to be movable towards the male pivot member for taking up wear, a horizontally movable wedge engaging a surface of said wearing element, a rod passing longitudinally through said wedge, a component helical spring in compression between said wedge and a shoulder on the portion of said rod which extends beyond the broad end of said wedge to urge the wedge in a given direction with respect to said rod, the other end of said rod extending from the narrow end of said wedge through an opening in said housing, and a second component spring under compression intermediate said housing and a shoulder on said other end of said rod for further urging said wedge in said given direction.

3. A pivot centre for articulated locomotives and bogie locomotives, comprising a male pivot member and a female pivot member, said female pivot member including a wearing element which is mounted so as to be movable towards the male pivot member for taking up wear, a horizontally movable wedge engaging a surface of said wearing element, a rod passing through a longitudinal bore hole of said wedge, a component helical spring in compression between a relatively fixed part and a shoulder on the end of said rod which extends beyond the narrow end of said wedge, and a second component helical spring in compression between a shoulder on the other end of said rod and a shoulder formed by counter sinking said bore hole from the broad end of said wedge, whereby said springs act in series on said wedge to bias it in the direction for moving said wearing element for taking up wear.

4. A pivot centre for articulated locomotives and bogie locomotives, comprising a female pivot member, a male pivot member extending downwardly into said female pivot member, said female pivot member including a wearing element mounted so as to be movable towards the male pivot member for taking up wear, a horizontally movable wedge engaging a surface of said wearing element, two component horizontal helical springs, a rod coupling said springs, whereby said springs act in series on said wedge to bias it in the direction for moving said wearing element for taking up wear, said female pivot member, wedge springs and rod being housed in an oiltight container which provides an oil bath, and into which said male member projects through an oil-tight seal.

5. A pivot centre for articulated locomotives and bogie locomotives, comprising a casting having a recess adapted to form an oil bath, a female pivot member mounted in said recess, a male pivot member extending downwardly into said female pivot member, said female pivot member including a wearing element mounted so as to be movable towards said male pivot member for taking up wear, a horizontally movable wedge mounted in said recess and engaging a surface of said wearing element, a rod passing through a longitudinal bore hole of said wedge and extending at its end beyond the narrow end of said wedge through a wall of said recess to the outside thereof, a component helical spring outside said wall and in compression between said wall and a shoulder on the said end of said rod, a second component helical spring in compression between said wedge and a shoulder on the other end of said rod, whereby said springs act in series on said wedge to bias it in the direction for moving said wearing element for taking up wear, a cover mounted on the outside of said wall and enclosing the

projecting rod portion and the first-named component spring, and a cover for said recess through which the male member projects in sealed relation.
